UNITED STATES PATENT OFFICE.

CHARLES H. HARKINS, OF ST. LOUIS, MISSOURI.

WATER-CLOSET VALVE.

SPECIFICATION forming part of Letters Patent No. 391,318, dated October 16, 1888.

Application filed April 13, 1888. Serial No. 270,529. (No model.)

To all whom it may concern:

Be it known that I, CHARLES H. HARKINS, of the city of St. Louis, in the State of Missouri, have invented a certain new and useful Improvement in Water-Closet Valves, of which the following is a full, clear, and exact description, reference being had to the accompanying drawings, forming part of this specification, and in which—

10 Figure I is, part in side view and part in vertical section, illustrative of my invention. Fig. II is an enlarged vertical section of the tank and the parts within it. Fig. III is a similar view showing the parts within the tank 15 in elevation and in a different position to that shown in Fig. II. Fig. IV is a detail view showing the main-valve-operating mechanism and illustrating its operation. Figs. V and VI are detail vertical sections.

20 My invention relates to certain improvements in valves for water-closets and mechanism for operating them; and my invention consists in features of novelty hereinafter fully described, and pointed out in the claims.

25 Referring to the drawings, 1 represents a tank; 2, the bowl, and 3 the water-pipe connecting the tank to the bowl.

30 4 represents the pipe through which water enters the tank. This is provided with a valve, 5, (shown in dotted lines, Fig. II,) having a stem, 6, connected to a lever, 7, pivoted at 8 to an arm, 9, on the pipe, and to the free end of which a float, 10, is connected. The pipe may be provided with a spout, 4½. The valve 35 opens downward, and as the water lowers in the tank the falling of the float opens the valve and allows an inflow of water.

11 represents a leg located inside the tank 1 and communicating with the pipe 3. This 40 leg is divided by a partition, 13, not extending entirely to the top of the leg, leaving a passage, 14.

45 15 represents a valve hinged at 16 to the leg 11, near the mouth of the pipe 3, and to this valve is connected the lower end of a rod, 17, the upper end of which is connected at 18 to one end of a lever, 19. As the end 20 of the lever 19 is raised the valve 15 is opened, as shown by dotted lines in Fig. II, and water from the tank 50 passes into the leg 11 and through the pipe 3 to the bowl. The lever 19 is preferably operated by means of a lever, 21, pivoted at 22 to

an arm, 23, secured to the top of the tank. The inner end of the lever 21 may be provided with a counter-balance, 24, and its outer end 55 is connected by means of a cord or chain, 25, to the seat 26 of the bowl. On the lever 21 is an arm, 27, which bears against an arm, 28, on the lever 19 as the outer end of the lever 21 is lowered. As the outer end of the lever 21 is lowered, 60 a projection, 29, on the arm 27 bears against the inclined face 30 of the arm 28 and forces the end 20 of the lever 19 upward, opening the valve 15. As the outer end of the lever 21 is still further depressed, a projection, 31, on the arm 27 bears against the lever 19 at 32 (see Fig. IV) and forces the end 20 of the lever 19 downward again, closing the valve 15. (See Fig. III.) Thus the valve 15 is closed almost as soon as it is opened, and the water that passes 70 through it at this time gives what is called the “forewash,” it not being sufficient to produce a siphon in the leg 11. Fig. III shows the valve closed and the levers 19 and 21 in the position they occupy after the outer end of the latter has been pulled down. Now, when the pressure is removed from the seat, the projection 29 bearing upon the projection 28, as shown at 40, Fig. III, raises the end 20 of the lever 19 and again opens the valve 15. On 80 this movement of the parts there is nothing that forces the lever 19 back to close the valve 15, but the valve is left to close by gravity, and thus a larger amount of water passes 85 through, and this flow of water creates a siphon in the leg 11, the water passing up on one side of the partition 13 and down on the other side into the pipe 3, as shown by the arrows in Fig. II. This flow of water continues until the siphon is broken, and as one way of breaking the siphon I have shown a number of holes, 41, in the wall 42 of the leg, all of these holes but one being closed by plugs 43. When the water in the tank is reduced until it comes to one of these openings which is not plugged, the 90 air entering breaks the siphon and the flow of water ceases. In the drawings I have shown four holes, the upper three being plugged. Any one of these three, however, may be opened and the plug placed in the lower hole, 100 and thus produce a quicker breaking of the siphon to give a less flow of water. This flow of water produces the long wash.

It is obvious that instead of having a single

leg divided by a partition a bent pipe could be used, one end of which would communicate with the pipe 3 and the other end not quite extending to the bottom of the tank, to leave 5 the space 41.

45 represents a pipe forming a communication between the upper portion of the leg 11 and the trap 46 of the bowl, and 47 represents a pipe leading from the pipe 45 down into the 10 leg 11, and preferably extending into the pipe 3. Located in this pipe 45 is a valve, 48, secured to one end of a lever, 49, pivoted at 50 to the leg 11, and to the other end of which is secured a rod, 51. To the rod is secured a 15 float, 52, preferably by means of a set-screw, 53, by which it may be adjusted up or down to open the valve 48 sooner or later. As the water falls in the tank in giving the long wash beneath the float 52 the float falls and opens 20 the valve 48. In doing so it allows air to enter the trap 46 and breaks the siphon in the trap to prevent the water being carried out of the latter at the close of the long wash. As soon as the water rises in the tank again the 25 float 52 rises and closes the valve 48.

As an additional security against the formation of a siphon on the forewash, I secure an arm, 60, to the lever 21, which comes against the lever 49 and opens the valve 48 as the 30 outer end of the lever 21 is depressed, thus effectually preventing the formation of a siphon on the forewash. When the pressure is removed from the seat, the arm 60 leaves the lever 49 and the valve 48 closes at once.

35 200 represents stop-plugs to limit the movement of lever 21.

It is obvious that the valve 48 may be utilized to break the siphon in the leg 11 and pipe 3, as well as in the pipe 45.

40 In Fig. V another means (in lieu of the valve 48 and its parts) is shown for breaking the siphon in the pipe 45. This consists of a branch, 201, communicating with the pipe 45 and having a sliding tube, 202, connected to it by a 45 stuffing-box, 203. The tube may be slipped up or down, and when the water (as it falls in the tank) reaches its lower end air will enter and break the siphon.

In Fig. VI is shown another means (in lieu 50 of the plugs 43) for breaking the siphon in the pipe 3, consisting of a pipe, 204, connected to the leg 11 and having a sliding tube, 205, connected to it by a stuffing-box, 206. The tube extends down into the tank, and by moving it 55 up or down the siphon may be broken sooner or later, as described.

I claim as my invention—

1. In a water-closet, the combination of the tank, bowl, water-pipe connecting the tank to the bowl, siphon within the tank communicating with said pipe, a valve for opening communication between the tank and pipe, a pipe for forming communication between the siphon and trap of the bowl, a valve in said trap-pipe, 55 and a float for operating the valve, substantially as and for the purpose set forth.

2. In a water-closet, the combination of the

bowl having a trap, the tank, a water-pipe forming communication between the tank and the bowl, a pipe extending from the trap of 70 the bowl into said water-pipe, and a valve situated above the normal water-level of said tank in said trap-pipe for admitting air to said trap and water-pipe, substantially as and for the purposes set forth.

75

3. In a water-closet, the combination of a tank, bowl, water-pipe forming a communication between the tank and bowl, and a pipe forming communication between the trap of the bowl and said water-pipe, a valve located 80 in said trap-pipe, and a float for operating the valve, substantially as and for the purpose set forth.

4. In a water-closet, the combination, with the tank, of a siphon for draining said tank, 85 valves 15 and 48 for starting and breaking the siphonic flow, respectively, an arm, 28, adapted to operate valve 15, a lever having an arm adapted to depress and pass said arm 28 and thereby open valve 15, a float adapted to hold 90 valve 48 closed, and a second arm on said lever adapted to sink the float when said lever is depressed, substantially as set forth.

5. In a water-closet, the combination, with the seat, a tank and a siphon in said tank, of 95 valves 15 and 48 for starting and breaking the siphonic flow, respectively, a float for holding valve 48 closed, an arm, 28, for operating valve 15, a pivoted lever, two arms on said lever, one adapted to depress and pass the arm 100 28 and the other to sink said float when the lever is rocked in one direction, whereby valve 48 will be opened and the valve 15 opened and closed, and when rocked in the opposite direction the float released and the valve 15 105 again opened to start the siphonic flow, said lever being attached to the seat and provided with a weight, substantially as set forth.

6. In a water-closet, the combination of the tank, bowl, and water-pipe forming communication between the tank and bowl, siphon located within the tank and communicating on one side with the said water-pipe and on the other side with the tank, valve for opening communication between the tank and pipe, 110 mechanism for operating the said valve, an air-valve located on top of said siphon and secured to one end of a pivoted lever, rod on said lever, and a float secured to said rod, substantially as and for the purpose set forth.

115

7. In a water-closet, the combination of a tank, bowl, water-pipe forming communication between the tank and bowl, siphon located within the tank, valve for opening communication between the tank and said water-pipe, 120 pipe 45 forming communication between the siphon and the trap of the bowl, pipe 47, extending downward into the siphon, valve 48, and a float for operating the valve 48, substantially as and for the purpose set forth.

125

8. In a water-closet, the combination of the tank, bowl, water-pipe forming communication between the tank and bowl, valve for opening communication between the tank and water-

130

pipe, and mechanism for operating the valve, consisting, essentially, of two pivoted levers, 19 21, to one of which said valve is connected, and the other of which is connected to the 5 seat of the bowl, the lever 19 having an arm, 28, with a face, 30, and the lever 21 having an arm, 27, with projection 29, adapted to depress and pass said face, and the projection 31, adapted to strike the arm 28 and lever 19 al-
ternately, substantially as and for the pur-
pose set forth.

9. In a water-closet, the combination, with

the tank, a bowl having a trap, and a siphon in said tank having one leg connected with said bowl, of a pipe connected to said trap and 15 extending into said siphon, a valve in said trap-pipe above the normal water-level of said tank, a pivoted lever connected to said valve, and an adjustable float connected to said le-
ver, as set forth.
